UNITED STATES PATENT OFFICE.

BERNARD MORGAN, OF RHINEBECK, NEW YORK.

PUPPET-VALVE AND SUPPORT THEREFOR.

SPECIFICATION forming part of Letters Patent No. 762,078, dated June 7, 1904.

Application filed October 5, 1903. Serial No. 175,740. (No model.)

To all whom it may concern:

Be it known that I, BERNARD MORGAN, a subject of the King of Great Britain, and a resident of Rhinebeck, in the county of Dutchess 5 and State of New York, have invented a new and Improved Puppet-Valve and Support Therefor, of which the following is a full, clear, and exact description.

This invention relates to a class of puppet- 10 valves in which the valve and its stem are held to play toward and from the seat by a cage through which fluid or liquid may pass, the volume of flow being controlled by the valve and determined by the distance inter- 15 vening the valve-face and seat therefor.

The object of the invention is to provide 20 novel details of construction for a puppet-valve of the class indicated and also for the supporting-cage that carries the valve-seat 25 which adapt the improved-valve for very reliable service, reduce wear and necessary repair to a minimum, and afford a simple practical device that is adapted for service either as a relief-valve or a feed-valve for steam, water, or gas used as a motive agent for stationary or automobile motors.

The invention consists in the novel construction and combination of parts, as is hereinafter described, and defined in the appended 30 claims.

Reference is to be had to the accompanying drawings, forming a part of this specification, in which similar characters of reference indicate corresponding parts in all the figures.

Figure 1 is a side view of the improved 35 valve and valve-cage. Fig. 2 is a sectional side view substantially on the line 2-2 in Fig. 3. Fig. 3 is a plan view of the device, and Fig. 4 is a sectional side view showing a 40 slightly-altered construction of the valve-support.

The valve-cage that supports the valve and its stem in operative relation to the valve-seat consists of an annular base-piece 5, having 45 a true lower surface *a*, that affords a seat for the valve, which will presently be described.

At a suitable point *b* above the seat *a* an offset shoulder is formed on the base-piece 5, that is thickened in its side wall to permit 50 the formation of said shoulder, and opposite

the shoulder *b* a circumferential flange *c* is integrally formed, that defines with its upper surface the upper side of the base-piece. The cage or valve-support also comprises a two-part cap-piece, the duplicate parts 6 6^a thereof 55 having contact on a line *d*, that coincides with the axis of the annular base-piece 5, and each cap-section is formed, essentially, as shown. The lower portions of the half-sections 6 6^a are semicircular and together form a cap-ring 60 having a radial flange *e*, that is true on the lower surface and adapted to seat upon the true upper surface of the flange *c* on the base-piece 5. The flange *e* at its inner edge merges on the lower side into a depending circular 65 wall *e'*, that bears upon the true horizontal face of the annular shoulder *b*, and to render these surfaces gas and liquid tight where they have contact they may with advantage be ground together. 70

In each cap-section 6 6^a an opening *g* is formed for the free passage of motor fluid therethrough, these passages or ducts leading into the chamber *g'*, formed partly in the base-piece 5 and partly in the joined cap-sections 75 6 6^a, as is shown in Figs. 2 and 4.

From the upper part of each half-section 6 6^a a semicylindrical flange projects, these flanges having straight edges that are extensions of the straight surfaces of the main lower portions of said cap-sections, so that when the latter are placed together on the line *d* the semicylindrical flanges will abut upon the same line, and the said flanges will together provide a guide-sleeve 7. 80

The upper portions of the cap-piece sections 6 6^a are preferably raised to give said cap-piece dome shape in its upper portion, and the base of the sleeve 7 extends down through the center of the raised part mentioned, so as to provide an orifice of equal diameter through the sleeve and cap-piece. 85

The valve consists of a circularly-edged disk or block 8, that is true on its upper surface at and near the edge, which surface may have contact with the seat *a* on the base-piece 5 and for effective surface should form a tight joint thereon. From the center of the valve 8 a stem 9 projects that is at a right angle with the upper surface of the valve-body, said stem loosely 90

100

fitting in the bore of the guide 7 and alined orifice in the cap-piece.

Upon the end of the valve-stem 9 that is opposite from that which is affixed to the valve-body 8 a circular head-flange 9^a is formed, said flange affording an annular shoulder that projects equally from the stem. The length of the stem 9 is so proportioned that a space is formed between the head-flange 9^a and the upper end of the guide-sleeve 7, this space determining the degree of opening had by the valve 8 when it is removed from its seat *a* and is arrested by the impingement of the head-flange upon the guide-sleeve.

15 A coiled spring 10 is mounted upon the stem 9 and has enforced engagement with its ends upon the head-flange 9^a and the cap-piece of the valve-cage at the base of the guide-sleeve 7, which the spring-coil encircles, and for effective service the strength of the spring must be sufficient to insure the seating of the valve 8 upon the annular seat *a* when pressure on the valve from gas or liquid that enters the chamber *g* through the openings *g* is relaxed.

20 25 It will be apparent that as the head-flange 9^a is formed integral with the valve-stem 9 it renders the bisection of the cap-piece of the valve-support necessary, as unless this provision is made it would not be possible to assemble the described parts of the valve-stem and valve-cage for use as a concrete device.

30 The valve is preferably employed as a means for inducting charges of motive fluid into the cylinder of a portable engine, such as the motor on an automobile, and to adapt it for such service it is affixed in proper position for receiving pressure of the motive agent (that may be gas, explosive vapor, or steam) directly upon the surface of the valve within the chamber *g*. The pressure of the gaseous motive agent upon the valve compresses the normally expanded spring 10 sufficiently to seat the head-flange 9^a upon the adjacent end of the guide-sleeve 7, which will correspondingly un-

40 45 seat the valve 8 and permit the motive agent to flow under pressure into the motor-cylinder or into a communicating explosion-chamber, if such a construction is employed.

50 It will be seen that the provision of an integral head-flange 9^a on the end of the stem 9 obviates a source of danger that is contingent upon the employment of washers and cotter-keys or screwed collars that are ordinarily placed on the end of the valve-stem to form 55 an abutment for the end of the retracting-spring, such as 10, as it will be impossible for the valve to be dislodged from its seat entirely or a greater distance than that permitted by the limited sliding movement of the 60 valve-stem 9, that is controlled by the head-flange 9^a.

In Fig. 4 is shown a modified construction of the valve-cage, which essentially consists in the provision of a male screw-thread *i*, that is 65 formed on the exterior of the depending an-

nular flange or wall *e* and that screws into the female thread *i'*, formed in the side wall of the recess that has the horizontal shoulder *b* for a bottom surface. It will be seen that the pressure of the motive agent and that of the spring 10 serves to retain the cap-piece of the valve cage or support in contact with the base-piece 5 when these parts are not joined together with the threads *i* and *i'*, and, as is represented in Fig. 2, said screwed connection being of advantage when the special application of the valve and its cage requires that the parts of the latter be positively secured together, as shown in Fig. 4.

The improved puppet-valve and its support 80 may be formed of any suitable metal forged or cast into form and subsequently finished by suitable means and can be produced at a moderate cost.

Having described my invention, I claim as 85 new and desire to secure by Letters Patent—

1. The combination with a circular valve having a flat upper side, a stem projecting centrally from the flat side of the valve, and a circumferential head-flange on the opposite 90 end of the valve-stem, of a valve-cage comprising an annular base-piece having a flat circumferential flange, a two-part cap-piece having a circumferential flange adapted to seat upon the flange on the base-piece, a bisected central sleeve projected from the cap-piece, said cap-piece being apertured between the circumferential flange and the guide-sleeve, said sleeve loosely receiving the valve-stem, and a coiled spring mounted upon the 100 sleeve and pressing the head-flange and cap-piece, so as to enforce contact between the circumferential flanges of the base-piece and cap-piece.

2. In a device of the described construction, 105 the combination with a circularly-edged valve having a flat side, a cylindrical stem projected centrally from the flat side of the valve, and an integral head-flange projecting peripherally from the end of the valve-stem, of a valve 110 support or cage that affords a seat for the valve, comprising an annular base-piece having a true seat for the valve on its lower end, a circumferential flange at the upper end thereof, an annular recess formed at the inner 115 edge of said flange, a two-part cap-piece having a radial flange at its edge, a depending flange entering the recess, the side walls of the recess and depending flange having threaded engagement, the cap-piece having dome 120 shape above the radial flange, and apertures in the dome-shaped portion, a two-part guide-sleeve central on the dome portion of the cap-piece said sleeve loosely receiving the cylindrical valve-stem, and leaving a space for play 125 of the valve, said space intervening the head-flange and the upper end of the guide-sleeve, and a coiled spring mounted upon the guide-sleeve, and contacting at its ends upon the head-flange and cap-piece.

3. In a device of the character described, the valve cage or support, comprising an annular base-piece having a valve-seat on its lower end, a radial flange on its upper end, 5 an annular recess at the inner edge of the radial flange, a two-part dome-shaped cap-piece having a radial flange near its base, a depending annular flange projecting below said radial flange, the depending flange entering the 10 recess when the radial flanges have contact with each other, the cap-piece having aper-

tures therein above the radial flange, and a two-part cylindrical guide-sleeve projected centrally from the top of the cap-piece.

In testimony whereof I have signed my name 15 to this specification in the presence of two subscribing witnesses.

BERNARD MORGAN.
